UNITED STATES PATENT OFFICE.

G. GABRIEL A. BOBRICK, OF LOS ANGELES, CALIFORNIA; MARY E. BOBRICK, ADMINISTRATRIX OF SAID GABRIEL A. BOBRICK, DECEASED, ASSIGNOR TO BOBRICK CHEMICAL COMPANY, OF LOS ANGELES, CALIFORNIA, A CORPORATION OF CALIFORNIA.

LIQUID DISPENSER.

Application filed June 6, 1922. Serial No. 566,246.

This invention has to do with improvements in liquid dispensers, and the particular form of the invention herein illustrated and described has been designed specifically for dispensing liquid soap; although it will be clearly understood that the invention is not necessarily limited to dispensing that particular kind of fluid. However, the invention will be more easily understood from an explanation of it as applied specifically to liquid soap dispensing.

I have encountered certain difficulties in making liquid soap dispensers, particularly in providing a positive action without any tendency to leakage, and in providing a simple and easily and economically manufactured device. It is very important in the manufacture of liquid soap dispensers that no leakage occur when the dispenser is not in use; it is also important to provide a dispenser of such form that the user is only able to obtain a measured amount of soap on each operation of the dispenser; it is important that the user cannot operate the dispenser in such a manner as to let soap run in a continuous stream through it. It is with these general objects in view that my present invention has been made.

It may be well at the outset to compare in a general way the device of my present invention with my former soap dispensing devices, as in that manner a clearer idea of the novelties of the present device may be had. For instance in my Patent No. 1,364,347, January 4, 1921, a pump mechanism is disclosed in which there are two valves, one in association with the plunger or piston and the other acting as a check valve to close the intake orifice on the down-stroke of the plunger.

In my copending applications, Serial No. 318,186, filed August 18, 1919, Serial No. 397,693, July 29, 1920, and Serial No. 446,885, filed February 21, 1921 there are disclosed means for closing the intake orifice by a pin moving at all times with and projecting from the plunger and adapted to move into the orifice when the plunger is pressed inwardly.

My present form of device attains all the above stated objects and provides a device that is easily and inexpensively manufactured. Its main feature in that direction is the provision of an inlet closing valve that is moved by the piston or plunger on its inward stroke for a short distance, then the in-

let closing valve remains stationary with the inlet closed while the piston or plunger continues its inward movement for the purpose of ejecting the liquid soap through the outlet. The inlet is closed at the very moment that the outlet at the other end is opened, and this prevents liquid running through the device in a continuous stream; and only a predetermined amount of soap can be obtained in the charge that is pressed out by the inward stroke of the plunger or piston. The action is positive, and no extreme accuracy or close fitting is required in manufacturing the parts.

Although there are other features of the invention that I will hereinafter explain they will best be understood from the following detailed description:

For the purpose of this detailed description of illustrative forms of the invention I now refer to the drawings, in which:

Fig. 1 is a longitudinal central section of one form of liquid dispenser, the parts being shown in their normal position; Fig. 2 is a similar view showing the parts in the position that they assume when the plunger is pressed inwardly; Figs. 3 and 4 are respectively similar views of another form of device; Figs. 5 and 6 are respectively similar views of another form of the device; and Figs. 7 and 8 are respectively similar views of another form of device.

Referring first to the form shown in Figs. 1 and 2 I show a tubular body 10 with a bore 11, screw threaded at 12, at one end for attachment to a soap supply pipe. At the other end of the body the bore is reduced as shown at 13, and this reduced portion of the bore is arranged to pass the stem 14 of the plunger or piston 15, which plunger is of a size to fairly fit bore 11. It will be understood that this fit need not be liquid-tight. A valve member 17, here shown in the form of a flexible sealing washer, is carried by the plunger as illustrated, in a position to press outwardly normally against a valve seat or sealing shoulder 18 at the entrance of the reduced bore 13. It will be understood of course that the provision of washer 17, in the valvular action here described, is only for the purpose of insuring at all times a tight seal. It will be readily understood that the plunger itself could bear against shoulder 18 with similar results. But it is not abso-

lutely necessary that the washer 17 be used, as the plunger itself may be made to bear against shoulder 18.

lutely necessary to make a valve or washer 17 and seat 18. The seat 18 is necessary to provide a stop for the plunger and the valve is a precaution to prevent leakage should 5 valve 36 get out of order or something should get under the valve. The outlet spout 19 communicates with the reduced bore 13; so that when the parts are in normal position, as shown in Fig. 1, soap cannot reach the outlet spout due to the sealing action of this 10 valve.

Plunger stem 14 is preferably somewhat smaller than bore 13 so as to provide a passage for the soap when the plunger is moved 15 inwardly. To prevent leakage of the soap outwardly around the plunger stem, I provide a flexible cup 20 that surrounds an enlargement or bead 22 around stem 14 and is held in position by a ferrule 23 that in turn 20 is held in place by the operating handle 25 screw-threaded on to stem 14.

The intake orifice of the device is located as shown at 30, in a bushing 31 threaded into the body near its inner end. This bushing 25 has a conical valve seat 30^a at its inner face around one end of intake orifice 30, and the correspondingly shaped conical end 33 of closure valve stem 34 forms a valve that is adapted to seat on the conical valve seat 30^a as 30 shown in Fig. 2. This stem 34 is loosely and slidably mounted in a bushing 35 carried in the rear end of plunger 15. Inside this bushing the valve stem 34 has a flange 36 and the valve stem is normally pressed rearwardly to 35 the position shown in Fig. 1, by spring 37, and in this position the flange, with an appurtenant flexible washer 36^a, forms a valve to close the bushing opening 35^a through which valve stem 34 loosely passes. Thus, in the 40 position shown in Fig. 1, the valve at 36—36^a is normally closed, and it is not opened until the instant valve 33 seats on valve seat 30^a to close the inlet orifice.

A flexible cup 45 surrounds the bushing 35, 45 as illustrated in the drawings, to make a tight joint with bore 11 and prevent liquid from passing around plunger 15. Spring 40 that presses the plunger forwardly is confined between bushing 31 and flange 35^b on bushing 35. Openings 60 serve to connect the interior of the hollow plunger head and the interior of bushing 35 with the space in bore 11 forward of the plunger.

In the normal position of the parts liquid 50 soap fills bore 11 to the left of the plunger. Upon inward movement of the plunger actuated by handle 25, the valve 33 shortly engages with the valve seat 30^a and closes the intake opening after only a very short inward 55 movement of the plunger. The valve at 17 has left the valve seat or shoulder 18; and then, at the same instant that the valve 33 closes the intake opening the valve at 36—36^a opens the opening at 35^a, allowing the liquid 60 to flow into and through bushing 35 on fur-

ther inward movement of the plunger. This liquid then, on further inward movement of the plunger, flows through openings 60 and into and through the bore 11 to the right of the plunger and thence out through outlet 19. 70 Upon return movement of the plunger the parts come back to their normal positions, and when the inlet opening 30 is finally opened, then the liquid soap flows in and fills the bore 11, to the left of the plunger ready 75 for another operation. It will be particularly noted that only a measured quantity of soap can be obtained at one operation, and that the device cannot by any possibility be put in any position to allow a continuous flow 80 of liquid. When the device is in its normal position the valve at 17 seals the outlet against any possibility of leakage or continuous flow. Furthermore, the possibility of any leakage or flow is prevented by the valve at 36—36^a 85 and this valve at 36—36^a is only opened at the instant the valve at 33—30^a is closed; and it is again closed at the very instant the inlet valve at 33—30^a is opened.

This dispenser that I have now just explained has several distinct advantages. It is positive in action; its outlet is positively and doubly closed when in normal inactive position, and its inlet is positively and tightly closed when the plunger is moved inwardly 90 and is, by the inherent nature and construction of the device, necessarily closed at the very instant the valve 36—36^a is opened. Furthermore, as I have explained, and as can readily be seen from the accompanying drawings, it is not necessary that great accuracy be used in manufacturing the various parts; and no great accuracy of fit is requisite at any point in the whole device. The exact distance between 33 and 30^a is of no consequence; as 95 the construction makes the valve at 36—36^a open at the instant 33 seats on 30^a, regardless of the normal distance between those two last mentioned parts.

In Figs. 3 and 4 I illustrate a modification 100 of the above described form. Here the intake orifice bushing 31 has a flexible valve seat washer 47 against which the cup-shaped valve 33^a on the end of intake closure valve stem 34 is adapted to seat when the plunger is moved 105 inwardly. A metal washer 46 bears against valve seat washer 47, and spring 40 in this case bears against metal washer 46. The inner end of valve stem 34 also has a small 110 guide stem 50 that extends into a bore 51 that extends forwardly into plunger stem 14, as illustrated. The action of this device is substantially the same as hereinbefore described, the valve at 33^a acting to close the intake orifice and the valve at 36—36^a acting to open 115 at the same instant that the intake orifice is closed. A small pin 38 extending from the rear end of valve stem 34 projects loosely 120 into opening 30 and acts as a guide for valve 33^a. In this form of device I have shown 125

slightly different packing means for plunger stem 14 in the bore 13, but as this packing means is substantially the same as that described in my application Serial No. 397,693, 5 it needs no description here.

In Figs. 5 and 6 I have shown another modification of the foregoing described forms. Here the plunger 15^a is fitted loosely in the bore 11 so that liquid soap may pass 10 around the plunger instead of passing through it. In addition to the packing cup 20 that remains at all times in bore 13, I provide another flexible cup at 21 that is fitted over an enlargement or bead 22 on the plunger 15 stem and is held in place by a ferrule 24, the other cup 20 being then fitted over the 15 end 22^a of this ferrule as illustrated. Cup 21 normally stands in bore 13 close to bore 11; and its position is such that when the inlet 20 closure valve is just closing the inlet orifice, then this cup 21 is just passing out of effective engagement with the bore 13; so that it then no longer seals the bore 13 and outlet 19. For instance it may be arranged that 25 cup 21 is, at that point of operation, just passing out of bore 13 into bore 11, or has at that time just passed sufficiently out into enlargement 13^a to allow liquid to pass around the cup and through bore 13 to outlet 19. 30

The intake closure valve is formed somewhat differently here. Valve stem 34 has a valve formed at its end, for instance by a flexible washer 33^b, that is adapted to seat 35 on an annular ridge or bead 30^b at the inner face of bushing 31 and surrounding intake orifice 30. In the operation of this device upon the first inward movement of the plunger this intake orifice is closed; and at the 40 same time the cup 21 passes out of the bore 13 to allow liquid to pass to outlet 19. Then on further inward motion of the plunger the liquid is pushed out through outlet 19. Upon the return movement the cup 21 seals the outlet 45 let at the same time that valve 33^b opens, thus preventing any possibility of a steady stream flowing through the device; and when the device is in its normal position the valve at 17 further seals the outlet.

In the forms shown in Figs. 7 and 8 there 50 is another slight modification in comparison with the forms in Figs. 5 and 6 to the extent that spring 37 is here placed around valve stem 34 outside the bushing 35, instead of inside the bushing 35 as in the other form. The inner end of the valve stem is then provided with a screw 65 to act as a stop to limit its spring impelled movement.

I claim:

60 1. In a liquid dispenser, the combination of body having a chamber therein and having a bore leading to its exterior from said chamber, a stem extending through said bore and formed with a handle at its outer end for manipulation, and said stem being

projectile into said chamber through the bore, an enlarged hollow head at the inner end of the stem within the chamber, said body having an intake opening for said chamber at its inner end and having an outlet opening 70 communicating with said bore at a little distance from the chamber; a valve member carried by the stem at the outer end of said enlarged head and adapted normally to press against a shoulder of the chamber wall around 75 the bore so as normally to seal the bore and the outlet opening from the chamber, a spring normally pressing the stem and its enlarged head outwardly, a plurality of packings on and surrounding the stem and 80 normally within the bore, one near the outer end of the bore and the other near the inner end of the bore and near the chamber, so that the second mentioned packing is carried into the chamber when the plunger is moved inwardly a little distance; and an intake opening closure member carried by said enlarged head adapted to be moved into closing relation to the intake opening when the plunger 85 and head are moved inwardly the distance 90 necessary to move said second mentioned packing out of the bore into the chamber, said closure member also having movement relative to the enlarged hollow head, and a spring acting between the head and the closure member tending to press the closure member toward the intake opening.

2. In a dispensing valve, the combination of a valve body having a discharge chamber provided with an inlet and a fixed outlet, a plunger mounted in the valve body and arranged to close communication between the discharge chamber of the valve body and the outlet thereof, a valve member slidably supported by the plunger, and provided with a 100 valve head, the valve member being moved by the plunger during a predetermined movement of the latter and arranged to close the inlet to the discharge chamber during the major portion of the movement of the 110 plunger.

3. In a dispensing valve, the combination with a valve body provided with a discharge chamber having an inlet valve seat and a fixed outlet, a plunger slidably mounted in 115 the valve body with the inner end thereof extending into the discharge chamber, a valve member slidably mounted in a bore formed in the inner end of the plunger, resilient means mounted on the valve member and 120 acting against the said inner end of the plunger, whereby said valve member may be moved against said inlet valve seat in the discharge chamber and close the inlet to the discharge chamber after a predetermined inward movement of the valve plunger and thereafter remain seated during a further inward movement of the plunger.

4. In a dispensing valve, the combination with a valve body provided with a discharge 130

chamber having an inlet valve seat and a fixed outlet, a plunger having valve means closing said outlet during a predetermined inward movement of the plunger, and means 5 carried by the plunger and movable therewith during said predetermined movement of the plunger and arranged to contact with said valve seat.

5. A dispensing device comprising a chambered body provided with an inlet port and an outlet port, a plunger in said body movable relatively to both of said ports, and adapted to close one of them, a valve movable relatively to the plunger and adapted to close 10 the other of said ports, said plunger being provided with a channel affording communication between the inlet port and the outlet port, and yielding pressure means for moving the plunger to a position in which it closes 15 one of said ports.

6. A liquid dispensing device in which is comprised a partition member and a body member removably engaging the same, said body member being provided with a longitudinal chamber, and the partition member being provided with a valve port affording communication between the body chamber and a supply conduit, a plunger movable longitudinally in the body chamber and having 20 a valve adapted to close the valve port, the body being provided with an outlet, the plunger being provided with a member cooperating with the wall of the body to induce suction through the valve port when the 25 plunger is moved outward, the plunger being provided with a channel affording communication between the valve port and the outlet, the plunger being adapted to close the outlet when in normal position, and means for operating 30 the plunger.

7. In a dispensing valve, the combination of a valve body having a discharge chamber provided with an inlet and an outlet port, a piston slidably mounted therein, said piston having a passageway formed in the inner end thereof establishing communication between the discharge chamber and a discharge passageway formed in the valve body, means on the piston normally sealing the discharge 45 passageway of the valve body, a stem adapted to seal said inlet at one end with the other end slidably engaging the piston in said passageway, resilient means for maintaining the piston in a normally outward inoperative position and sealing the valve body discharge passageway, other resilient means for normally maintaining said stem in an extended position relative to the piston and a lost motion connection between the piston and stem 50 for normally maintaining the stem out of contact with the inlet.

8. In a dispensing valve for liquid soap, a valve body having a displacement chamber provided with an inlet port at one end there-

of, a piston bearing against the side walls of 65 said displacement chamber, said valve body having an outlet port normally closed by the piston and the piston having a longitudinal recess and a lateral passageway communicating therewith and opening adjacent the wall 70 of the body to form a discharge chamber, a stem supported at one end in the piston recess and arranged to close said inlet port, a connection between the piston and stem for normally maintaining the stem out of contact 75 with the inlet port, resilient means within the displacement chamber for holding the piston in outlet port closing position and other resilient means located in the recess in the piston bearing against the stem and arranged to cause the stem to close the inlet port when the piston is manipulated.

9. In a dispensing valve for liquid soap, the combination of a valve body having a displacement chamber provided with an inlet port, a piston in said chamber, an outlet port formed in the body normally closed by said piston, a stem extending into the piston having a lost motion connection therewith and arranged to close the inlet port, resilient means in the displacement chamber for holding the piston in outlet port closing position and for maintaining the stem out of contact 85 with the inlet port, and other resilient means in the piston, normally restrained, and arranged to act on the stem to close the inlet port when the piston is moved to reduce the area in said displacement chamber and to 90 open the outlet port.

10. In a dispensing valve, the combination 100 of a valve body having a discharge chamber provided with an inlet and an outlet port, a piston slidably mounted therein, said piston having a passageway formed in the inner end thereof establishing communication between the discharge chamber and a discharge passageway formed in the valve body, means on the plunger normally sealing the discharge passageway of the valve body, a stem adapted to seal said inlet at one end with the other end slidably engaging the piston in said passageway, resilient means for maintaining the piston in a normally outward inoperative position and sealing the valve body 105 discharge passageway, other resilient means for normally maintaining said stem in an extended position relative to the piston and a lost motion connection between the plunger and stem for normally maintaining the stem out of contact with the inlet; said lost motion connection including valve means which seals the piston passageway when the stem is in its position extended relatively to the piston.

In witness that I claim the foregoing I 125 have hereunto subscribed my name.

GABRIEL A. BOBRICK.
